US00D599346S

(12) **United States Design Patent**
Thia et al.

(10) **Patent No.:** **US D599,346 S**
(45) **Date of Patent:** **** Sep. 1, 2009**

(54) **USB STORAGE DEVICE HOUSING**

(75) Inventors: **Kong Beng Terang Thia**, Singapore (SG); **Wei Loon Ng**, Singapore (SG); **Pei Koh Lee**, Singapore (SG); **Kah Liang Gan**, Singapore (SG)

(73) Assignee: **Seagate Technology LLC**, Scotts Valley, CA (US)

(**) Term: **14 Years**

(21) Appl. No.: **29/317,385**

(22) Filed: **Apr. 29, 2008**

(51) **LOC (9) Cl.** **14-02**

(52) **U.S. Cl.** **D14/356**

(58) **Field of Classification Search** **D14/411, D14/384-385, 518, 348-349, 432-436, 299, D14/402, 242, 351-358, 496, 155-156, 240, D14/301, 313, 363, 368, 370, 137, 167-168; D3/201, 273; D13/149, 184; 710/300-301; 439/131, 136, 140-141; 361/684-686; 360/97.01**

See application file for complete search history.
